UNITED STATES PATENT OFFICE.

JOHN C. SCHELTER, OF ROCHESTER, NEW YORK.

LAST.

Application filed October 23, 1924. Serial No. 745,504.

The present invention relates to lasts and more particularly to the type where the fore part and the heel part are connected for relative movement. An object of this invention is to provide an improved construction whereby the last is locked yieldingly in an expanded condition. Another object of this invention is to provide a construction in which a roller on one part cooperates with a yielding surface on another part for the purpose of holding the last in an expanded condition. Still another object of the invention is to provide a construction in which the last parts are pivotally connected by a bonding plate which carries a surface extending laterally from opposite sides of the plate for cooperating with a resilient device to hold the last in an expanded position. Still a further object of the invention is to provide, in a hinge last which has a resilient device on one part engaged by a surface on another part to hold the last expanded, a construction of the resilient member engaging surface which will reduce the wear on the resilient member to a minimum.

To these and other ends, the invention consists of certain parts and combinations of parts, all of which will be hereinafter described: the novel features being pointed out in the appended claims.

In the drawings:

Fig. 1 is a fragmentary section of a last showing the latter in an expanded condition;

Fig. 2 is a similar view showing the last collapsed;

Fig. 3 is a view similar to Fig. 1 showing the bonding member and the resilient member engaging-device thereon removed; and

Fig. 4 is a fragmentary section through the two last parts showing the metal parts in plan.

Referring to the illustrated embodiment of the invention, 1 indicates the fore part and 2 the heel part. These parts are hingedly connected together, in this instance, by a bonding member in the form of a plate 3 which through a pin 4 is pivotally connected to the fore part and through pins 5 is rigidly connected to the heel part, the fore part having a kerf 6 in which the plate operates and the heel part having a kerf 7 in which the bonding plate is held. In order to remove the strain from the pivot 4, cooperating bearing surfaces are provided on the fore part and the heel part. In this in-

stance, a convex cylindrical surface 8 is formed on opposite sides of the kerf 6 concentric with the center of the pivot pin 4 and a concave cylindrical surface 9 is formed on the heel part 2 concentric with said pivot pin 4, so that with the turning of the last parts relatively the plate 3 turns on the pin 4 and the heel part bearing 9 turns on the convex bearing surface 8 of the fore part.

With the end in view of locking the last in an expanded condition, locking means is employed which, in this instance, embodies a resilient device preferably carried by the fore part and preferably in the form of a split resilient metal tube 10 extending transversely of the last in eccentric relation to the pivot pin 4, for bridging the kerf 6, the plate 3 having a slot 11 which permits the movement of the heel part relatively to the transversely extending tube 10. Mounted on the heel part is a device which cooperates with the resilient tube or device to hold the last in an expanded condition. This device, in this instance, is in the form of a roller 12 mounted to turn in a recess 13 in the plate 3, said recess communicating with the slot 11 and being of segmental circular form, its wall being more than 180° so that the roller is locked in the plate and, at the same time, projects into the slot 11 at such a distance that, when the last is moved toward expanded condition, the periphery of this roller 12 will engage with the yielding and resilient device 10 and place the same under a stress so that as the final expanded condition is reached, the roller while still engaging the tube will have passed over the high point of the tube and the last will be yieldingly held in expanded condition.

Upon the collapsing of the last, the roller moves over the yielding and resilient tube 10 to a position out of engagement with said tube, as illustrated in Fig. 2. The roller extends from opposite sides of the bonding plate 3 so that a bearing surface is provided which is wider than the plate, and, as a consequence, the wearing on the yielding and resilient device 10 is reduced to a minimum and, at the same time, movement of the last to and from expanded condition is facilitated as the roller turns in passing over the high point of the yielding and resilient device 10.

What I claim as my invention and desire to secure by Letter Patent is:

1. A last comprising a fore part, a heel

part, bonding means connecting said parts to permit relative movement for the expansion and the collapsing of the last, a resilient device carried by one of said parts, and a 5 roller carried by the other part and cooperating with said resilient device.

2. A last comprising a fore part, a heel part, bonding means connecting the parts to permit relative movement for effecting the 10 collapsing and the expansion of the last, a transversely extending resilient member carried by one of said parts, and a roller having its axis extending transversely of the other part and cooperating with the transversely 15 extending yielding device to hold the last in an expanded condition.

3. A last comprising a fore part, a heel part, a bonding member pivotally connected to one of said parts and mounted to 20 swing with the other part, a resilient device carried by the part with which the bonding member is pivoted, and a roller carried by the bonding member and cooperating with 25 said resilient device to hold the last in an expanded condition.

4. A last comprising a heel part, a fore part, a bonding member connecting said parts and permitting relative movement between them for the expansion and collapsing 30 of the last, said bonding member having an opening, a resilient device carried by one of said last parts and extending through said opening, and a roller carried by the bonding member and cooperating with said resilient 35 device.

5. A last comprising a heel part, a fore part, a bonding member connecting said parts and permitting relative movement between them for the expansion and collapsing 40 of the last, said bonding member having an opening, a resilient device carried by one of said last parts and extending through said opening, and a roller carried by the bonding member and cooperating with said resilient 45 device, said roller extending from opposite sides of the bonding member.

6. A last comprising a heel part, a fore part, a bonding member connecting said parts and permitting relative movement between them for the expansion and collapsing 50 of the last, said bonding member having an opening, a resilient device carried by one of said last parts and extending through said opening, and a roller carried by the bonding member and cooperating with said resilient 55 device, said roller having greater width than the bonding member.

7. A last comprising a fore part, a heel part, a bonding member connecting said parts to permit the collapsing and expansion 60 of the last, a bearing surface carried by said bonding member and projecting laterally from opposite sides of said bonding member, and a device carried by one of said last parts and yielding transversely when engaged by the bearing surface to permit the latter to lie on either side of the yielding device and to engage with the device to hold 65 the last in an expanded condition.

8. A last comprising a fore part, a heel part, a bonding member connecting said parts together to permit them to move relatively for the expansion and collapsing of the last, said bonding member having an opening, a split resilient tube carried by one 70 of said last parts and extending through the opening, and a roller mounted to turn on the bonding member and projecting from opposite sides of the latter to cooperate with said split resilient tube to hold the last in expanded 75 condition.

9. A last comprising a fore part, a heel part, a bonding member connecting said parts to permit the collapsing and expansion of the last, a bearing surface carried by the 80 bonding member and projecting laterally from opposite sides of the bonding member, and a split resilient tube carried by one of said last parts and adapted to be transversely compressed by the bearing surface upon a 85 relative movement between the last parts.

JOHN C. SCHELTER.
